US00D907204S

(12) **United States Design Patent** (10) Patent No.: **US D907,204 S**
(45) Date of Patent: **** Jan. 5, 2021**

(54) **LIGATION CLIP**

(71) Applicant: **Covidien LP**, Mansfield, MA (US)
(72) Inventors: **Roy J. Pilletere**, North Haven, CT (US); **Justin Thomas**, New Haven, CT (US); **Matthew A. Dinino**, Newington, CT (US); **Saumya Banerjee**, Hamden, CT (US); **Gregory R. Morck**, Haddam, CT (US); **Eric Brown**, Haddam, CT (US)

(73) Assignee: **Covidien LP**, Mansfield, MA (US)

(**) Term: **15 Years**

(21) Appl. No.: **29/700,496**

(22) Filed: **Aug. 2, 2019**

(51) LOC (13) Cl. **24-02**

(52) U.S. Cl.

USPC **D24/143**

(57) **CLAIM**

The ornamental design for a ligation clip, as shown and described.

DESCRIPTION

FIG. 1 is a side perspective view of the ligation clip in accordance with an exemplary embodiment of the design; FIG. 2 is a right side view of the ligation clip shown in FIG. 1;

FIG. 3 is a bottom view of the ligation clip shown in FIG. 1;

FIG. 4 is a top view of the ligation clip shown in FIG. 1; FIG. 5 is a left side view of the ligation clip shown in FIG. 1;

FIG. 6 is a front view of the ligation clip shown in FIG. 1; and,

FIG. 7 is a rear view of the ligation clip shown in FIG. 1. The broken lines shown in the figures are included for the purpose of illustrating portions of the ligation clip and form no part of the claimed design.

1 Claim, 4 Drawing Sheets
